DIE SET LEADER PINS AND LEADER PIN BUSHINGS

Kasimir Janiszewski, Hales Corners, Wis.

Application December 21, 1951, Serial No. 262,815

20 Claims. (Cl. 164—118)

This invention relates to improvements in die set leader pins and leader pin bushings having clearances variable in the course of their relative movement.

One of the objects of the invention is to facilitate separation of the platens of a die set without cramping the leader pins in their respective bushings. For this purpose, leader pin and bushing assemblies having variable clearance between the respective leader pins and bushings are provided.

The problem of die set leader pins cramping in their punch holder bushings is particularly noteworthy whenever the punch holder of the die set is removed for punch changing or other purposes. The punch holder is conventionally guided by a plurality of leader pins, varying in number, but frequently four, one at each corner of the punch holder. As the punch holder is lifted from the die set, by a crane or the like, it may, as it is about to clear the top ends of the leader pins, tilt or cant to withdraw completely from one pin before clearing the remaining pins, and thus cramp or seize and even bend the other leader pins, or break or crack the bushings. Even if the punch holder does not prematurely clear one pin, the gradual reduction in bearing surface may permit the punch holder to tilt and cramp or bend one or all of the pins.

Accordingly, it is one object of the present invention to obviate this difficulty by providing the leader pins with immediately available clearance during the course of platen separation either between the bushings and the leader pins, or between the leader pin cores and separable sleeve portions thereof, or both, thereby eliminating the possibility of cramping.

Another important object of the invention is to provide leader pins and bushings having variable clearance to slidably engage with precision fit only during that critical portion of the punch holder stroke when the punch is engaging the work, and are relatively free of close contact during other and less critical portions of the punch holder stroke.

For these purposes a leader pin and bushing sleeve assembly is provided with complementary mating surfaces which provide close guidance at axially remote points but afford increased clearance immediately as the platens separate. In preferred embodiments of the invention, the tapered surfaces comprise stepped cylindrical surfaces rather than surfaces of frusto-conical form. In all embodiments, however, the leader pin and bushing sleeve have complementary surfaces which have clearance progressively increasing in the direction of withdrawal of the punch holder from the die shoe and decreasing in the direction of work engagement.

A specific object is to provide, in one embodiment of the invention, a sectional leader pin having internally tapered complementary cored and socketed sections with coupling means therebetween.

Other objects and advantages of the invention will be more apparent to one skilled in the art upon an examination of the following disclosure.

2

In the drawings:

Fig. 1 is a perspective view of a die set having separable platens and leader pin and bushing sleeve assemblies embodying the invention.

5 Fig. 2 is an enlarged vertical cross section through a portion of the die set and one embodiment of a sectional leader pin and bushing sleeve assembly, portions of the leader pin being shown in elevation and other portions being shown in section to expose details of construction.

10 Fig. 3 is an axial cross section through the leader pin only of Fig. 2, the respective leader pin sections being shown in separated position.

Fig. 4 is a view partly in elevation and partly in cross section of a modification of the sectional leader pin shown in Figs. 2 and 3.

15 Fig. 5 is a fragmentary view of a still further modification of a sectional leader pin embodying the invention.

Fig. 6 is a vertical cross section through a portion of a die set having a leader pin and bushing sleeve assembly with complementary stepped cylindrical bearing surfaces, the leader pin being shown in elevation.

20 Fig. 7 is a view similar to that of Fig. 6 showing a modification in the bushing sleeve.

25 Fig. 8 is a further modification of the device of Fig. 6.

Fig. 9 shows a modification of the device of Fig. 2, showing a different form of sectional leader pin.

30 Fig. 10 is a different axial cross sectional view of the device of Fig. 9, showing the respective leader pin sections in the course of separation.

35 Fig. 11 is a cross sectional view through a modified form of the device shown in Fig. 9.

Fig. 12 is a vertical cross section through a portion of a die set fitted with a modified form of a tapered leader pin and bushing embodying the invention.

40 Fig. 13 is a cross sectional view taken along the lines 13—13 of Fig. 12.

A die set having separable platens comprising a die shoe 20 and punch holder 21 is diagrammatically shown in Fig. 1. As best indicated in Fig. 2, the die shoe normally carries a die, illustrated diagrammatically at 22, and has at least one upstanding leader pin 25. The punch holder carries a punch, illustrated diagrammatically at 23, and is provided with a bushing in which the leader pin is slidable to guide the punch as it reciprocates with the punch holder to coat with the die 22 upon the work illustrated diagrammatically at 24.

45 Individual leader pin assemblies, usually two, three or four in number, are normally provided at each corner of the die set, as best shown in Fig. 1. Prior to the present invention, the respective leader pins and punch holder bushings were made with complementary precision fitted bearing surfaces extending for substantially the full height of the punch holder and full length of the leader pins.

50 The improved leader pin and bushing assemblies illustrated in the accompanying drawings, and which are hereinafter described, all are structurally designed to provide for lateral clearance between the leader pin and bushing when the punch holder is separated from the die shoe. Several embodiments of leader pin and bushing taper will be hereinafter described.

60 Some of these embodiments comprise complementary frusto-conical mating surfaces, and other embodiments comprise stepped complementary cylindrical surfaces. I choose to denominate the configuration of these various modifications by a generic term 65 "taper," and such term will be understood as used throughout the specification and claims, except as otherwise indicated, to mean complementary mating surfaces of progressively smaller diameter in the direction of punch holder withdrawal.

70 In the preferred construction shown in Figs. 2 and 3, a sectional leader pin having a core section 25 is provided with a head 26 having discontinuous upwardly tapered

frusto-conical surfaces 27 and 28. Sleeve section 31 is provided with a cylindrical bore 33 and a communicating tapered bore or inner surface 32 complementary with the head surfaces 27 and 28.

At the junction of the cylindrical bore 33 and tapered bore 32, an apertured and countersunk plug 34 is inserted to serve as a seat for the head of a screw 35 which couples the sleeve section 31 and the core section 25 of the leader pin. Plug 34 is rotatably keyed to sleeve 31 by means of a snap expansion ring 38 which fits within the annular space provided by aligned peripheral grooves 36 and 37 in the plug and sleeve, respectively.

Head 26 of the leader pin section 25 is axially tapped at 41 to receive the threads of coupling screw 35, the head of which is seated in the countersunk aperture 42 in the plug 34. The head of screw 35 is provided with a socket 43 to receive a socket wrench such as the wrench 44 shown in Fig. 3. In order to develop axial thrust between the sleeve and the head sections to separate these sections, plug 34 may be shouldered above the head of the screw, whereby turning the screw in a direction to remove it from tap 41 will exert thrust against the plug to separate the sections. In the embodiment of Figs. 2 and 3, the shoulder is provided by upsetting portion 46 of the plug near its top surface over the counterbore, an apertured washer 45 being first positioned over the screw head and below the top surface of the plug.

In the embodiment of Fig. 5, a welsh plug 48 may be used to provide the shoulder in lieu of upsetting the plug. Plug 34 is provided, in its counterbore 42, with an undercut peripheral groove 47 within which the centrally apertured welsh plug 48 may be driven to substitute for the washer 45 of Figs. 2 and 3 and to provide the shoulder against which the head of the bolt 35 acts. The function of the shoulder is best illustrated in Fig. 3, where the sleeve section 31 has been partially lifted from the core section 26, thus laterally as well as axially clearing the complementary tapered frusto-conical surfaces 32 and 27, 28.

A somewhat modified form of the sectional leader pin is shown in Fig. 4 wherein the sleeve 51 of the sectional leader pin is internally threaded at 52, and is provided with a plug 53 complementarily threaded at 54. The threads hold the parts together, as compared to the snap ring arrangement of the embodiments of Figs. 2 and 3. In the embodiment of Fig. 4, however, plug 53 may be advanced axially on its threads toward the top of the leader pin core 55. Upon contact of the downwardly projecting boss 56 of the plug with the core top, axial thrust is developed to separate the sleeve and core sections.

By reason of the threaded connection of the sleeve section 51 and plug 53, the coupling screw 57 need not be used to separate these parts. Accordingly, the plug counterbore 58 is smooth-walled and not provided with a shoulder. The plug 53 is, however, provided with sockets 59 to receive a wrench to turn the plug respecting the sleeve section 51.

A still further sectional leader pin modification is shown in Figs. 9, 10 and 11 wherein the leader pin comprises an anchorage section 61 having a head 62 with a continuous frusto-conical tapered surface 63 mating with the complementary frusto-conical tapered bored surface 64 of sleeve section 65 of the pin. Sleeve section 65 has an integrally formed transverse web 66, as distinguished from the separate plug 34 in the embodiment of Fig. 2, and which constitutes the base of the socket 64. Web 66 is provided with a central aperture 67 and a counterbore 72 through which a screw 68 extends to threaded engagement with tap 71 of core 62. Counterbore 72 is threaded at 73 for a purpose to be hereinafter described in more detail.

Screw 68 has a socketed head 74, of less outer diameter than the web counterbore 72. Accordingly, axial movement and rotation of the head 74 is not interfered with by

the thread 73. Screw 68 serves to couple the complementary tapered socketed and cored sections of the leader pin. A transverse aligning pin 75 may be provided at the junction of the socketed and cored leader pin sections to assure uniform registration of the sectional parts.

At such times as it is desired to clear the socketed and cored sections of the leader pin, as incident to withdrawal of the punch holder 21 from the die shoe 20, screw 68 may be removed and replaced by a jack stud 76 (Fig. 10) having an enlarged head 77 with threads 78 engaging the threads 73 of the counterbore 72. Head 77 is provided with a central socket 81 to receive a socket wrench 82 whereby separating thrust may be developed between the threads 73 in the socketed section 65 of the leader pin and the cored section 61 of the leader pin through the unthreaded jack stud 76. As clearly shown in Fig. 10, separation of the mating leader pin sections will result in lateral as well as axial clearance between the frusto-conical surface 63 on the core 62, and the mating frusto-conical surface 64 on the socketed section 65 of leader pin.

If, during use of a die set, the leader pin section 65 seizes in bushing 91, the screw 68 will break to permit leader pin section 61 to withdraw, with constantly increasing clearance, from the tapered socket in section 65, thus precluding damage. Screws 35, 57 and 88 may be frangible for the same purpose.

A somewhat modified form of the device shown in Figs. 9 and 10 is shown in Fig. 11. In this modification, the head section 83 of the leader pin is provided with a smooth wall counterbore 84 having an internally facing groove 85 near its top end to receive a snap ring 86 which provides an upper shoulder against which the socketed head 87 of screw 88 may act. In this manner the same screw 88 accomplishes the function of the threaded screw 68 in Fig. 9 and the jack screw 76 in Fig. 10.

In the embodiments of the invention shown in Figs. 9, 10 and 11, the punch holder 21 is provided with a conventional continuously cylindrically walled bushing 91 complementary with the cylindrical outer wall or surface 92 of the socketed portion of the sectional leader pin. Accordingly in these embodiments the leader pin and bushing are in bearing relation throughout the normal range of such holder reciprocation.

In the embodiment of Fig. 2, however, provision is made to permit the leader pin to ride free in the bushing except at the critical point in the stroke where the dies coact upon the work. The punch holder bushing comprises axially spaced cylindrically walled collars 93 and 94, the collar 93 having an inner cylindrical surface 95 of smaller diameter than the inner cylindrical surface 96 of the collar 94. A spacer 97, of greater internal diameter than the collars, separates the collars 93 and 94. An external washer 98, of still greater internal diameter, holds the collars and spacer assembled against the annular shoulder 99 of the punch holder. The washer 98 is held against the under surface of the punch holder 21 and against the under surface of the collar 94 by one or more screws 101. The external surface of the socketed portion 31 of the leader pin is stepped to provide cylindrical surfaces 102 and 103, said surfaces being complementary with the cylindrical surfaces 95 and 96 of collars 93 and 94, respectively.

By reason of the spacing of collars 93 and 94, bearing engagement of their inner surfaces 95 and 96 with leader pin surfaces 102, 103 occurs in only a short range of punch holder reciprocation. The leader pin 25 is so positioned in die shoe 20 that these bearing surfaces do not come into engagement until the dies are about to coact upon the work. Accordingly, the leader pin acts as a guide only during the short period of the stroke of the punch holder when accurate guiding is of utmost importance. At all other times, the punch holder is relatively free and clear of the leader pin. In this manner

wear on the pin and bushing is greatly reduced and cramping becomes virtually impossible because the complementary bearing surfaces at opposite ends of the leader pin clear simultaneously in response to the first withdrawal movement.

In the embodiments of the invention shown in Figs. 6 and 7 the leader pin is a one piece construction, the conical tapers and screw being omitted. Instead, the upward taper on the leader pin 104 is in the form of stepped cylindrical surfaces 105, 106 and 107, the respective surfaces being of progressively smaller diameter in the direction of punch holder withdrawal. These stepped leader pin's surfaces mate with complementary stepped cylindrical bushing sleeve surfaces. In the embodiment of Fig. 6, the bushing bearing surfaces comprise the stepped surfaces 108, 109, 110. These surfaces are inwardly embossed on common sleeve 113 to progressively smaller diameters in the direction of punch holder withdrawal. Common sleeve 113 is further provided with an outturned bottom flange 114 which abuts the bottom surface of the punch holder 21 to position the sleeve respecting the punch holder. Sleeve 113 is normally held within the punch holder aperture 112 by a press fit.

In the embodiment of Fig. 7, the stepped complementary cylindrical bushing surfaces 115, 116 and 117 comprise the inner annular peripheries of axially spaced collars or rings which are separate from, but axially spaced by, spacer sleeves 118 and 119. The sleeves and collars are held in assembly against the shoulder 120 of the punch holder by an annular washer 121, similar to washer 98 in Fig. 2.

In either of the embodiments of Figs. 6 and 7, the bearing surfaces of the punch holder bushing or sleeve comprising the respective collars or embossments are substantially spaced axially. The leader pin is also so positioned that these bearing surfaces do not contact the leader pin surface until near the end of the downward stroke of the punch holder. Accordingly, almost immediate lateral, as well as axial, disengagement of the leader pin cylindrical bearing surfaces from the punch holder bushing or sleeve cylindrical bearing surfaces will occur after upward movement of the punch holder has been initiated. In this manner, lateral clearance between the leader pin and punch holder bushing is developed by reason of the stepped complementary surfaces and smooth withdrawal of the punch holder from the die shoe without cramping or seizing of the bushing against the leader pin is facilitated.

The embodiments of Figs. 6 and 7 are also characterized by cam action between the respective bearing surfaces on the punch holder bushing and leader pin during the portions of punch stroke when leader pin guidance is most necessary. At all other times, the leader pin is free and clear of bearing contact with the punch holder bushing.

In the embodiment of Fig. 8, the leader pin 124 is provided with stepped cylindrical surfaces of different diameters which comprise axially spaced annular collars 125 and 126 which are slipped over a central core 127 of the leader pin. The leader pin is provided at the lower base of the core 127 with a shoulder 128 against which the bottom collar 125 seats. Spacer sleeve 129 axially separates the respective collars 125 and 126. Top washer or plate 132, held to the leader pin by screw 133, holds the collars and spacer in unitary assembly against the shoulder 128. In this embodiment, the punch holder bushing also comprises axially spaced collars 134 and 135 having stepped cylindrical surfaces complementary with the stepped cylindrical surfaces of the leader pin collars 125 and 126. Collars 134 and 135 are axially spaced by the spacer 136. The respective collars 134 and 135 and spacer 136 are held against punch holder shoulder 137 by means of an external washer 138, which bears against the under surface of the punch holder 21.

As in the embodiments of Figs. 6 and 7, the Fig. 8 embodiment comprises leader pin and punch holder bear-

ing surfaces stepped in the direction of withdrawal of the punch holder whereby to provide for lateral as well as axial clearance between the respective bearing surfaces in all positions other than the immediate proximity to its lowermost position of the punch holder. As aforesaid, this relation of parts prevents punch holder cramping and provides cam action only when accurate leader pin guidance is required.

In all appropriate embodiments, by forming the respective bearing surfaces on removable collars, as distinguished from forming them integrally with the bushing sleeve or leader pin proper, ready replacement of individual worn collars is made possible, thus reducing maintenance costs.

In the embodiment of the invention shown in Figs. 12 and 13, the leader pin 141 is provided with an upwardly frusto-conical tapering surface 142, and the punch holder bushing 143 is provided with a complementary tapering bore 144. Accordingly, movement of the punch holder 21 from the die set will clear the punch holder bushing 143 and mating leader pin surfaces in the manner aforesaid to prevent seizing. As the tapers mate only at one point in punch holder stroke this arrangement of parts precisely aligns the punch holder and die shoe at the bottom of the punch holder stroke when accuracy is desired, but permit the leader pin to separate from its punch holder bushing at all other times.

In order to adjust the moment at which the complementary tapers mate, in accordance with the height of the work in the die shoe, the leader pin in the embodiment of Figs. 12 and 13 provided with a clamp mounting in which the pin is vertically adjustable. The clamp mounting comprises a sleeve 145 mounted in the punch holder bore 140. The sleeve 145 is split along one side margin at 146 and is provided with an encircling collar 147 having a clamp arrangement comprising a nut 148 and bolt 149. The diameter of the sleeve 145 may thus be changed whereby to act as a clamp for the leader pin 141. In this manner leader pin 141 may be raised or lowered in its mounting, and the height of the pin adjusted so that the taper on its upper surface will mate with the punch holder bushing taper at the precise moment that the punch is at its lowermost position in its stroke. In the other embodiment of the invention, the leader pin need not be adjustably mounted as the surfaces which bear are cylindrical, thereby permitting axial sliding movement of the respective bearing parts.

In all embodiments of the invention where frusto-conical tapers between the leader pin core and leader pin sleeve are shown, the preferred taper respecting the axis of the leader pin is one and one-half inches per lineal foot. The angle of the tapered sides with the leader pin axis is thus three degrees, thirty-four minutes, and thirty-five seconds; the included angle of the tapered sides being seven degrees, nine minutes and ten seconds. Such an angular relationship will permit the respective frusto-conical tapered parts to adhere under all normal circumstances but to separate easily upon the exertion of axial thrust between the mated parts. While other tapers would provide satisfactory clearances upon withdrawal of the punch holder, the stated taper is preferred because of its particular aforesaid characteristic.

From the foregoing description, taken in connection with the accompanying drawings, it is clear that a novel form of leader pin and punch holder bushing having complementary tapered surfaces, which may either be of frusto-conical or of stepped cylindrical form, has been provided whereby lateral as well as axial clearance between the parts is developed upon separation thereof. The particular structures of the devices shown in Figs. 2, 3, 4, 6, 7, 8, 12 and 13 also provide for cam action of the leader pin bearing surfaces with the punch holder bushing bearing surfaces in a narrow range of punch holder movement.

I claim:

1. In a die set having separable platens, the combination with a leader pin fixed to one of said platens, of a

sleeve movable respecting said leader pin with the other of said platens, said pin and sleeve having complementary mating surfaces which are of slightly smaller diameter adjacent their respective upper ends than adjacent their lower ends, whereby separation of said platens will cause lateral disengagement of said surfaces, the said surfaces being in sufficient proximity for effective pin guidance at all points of pin movement within the sleeve and having close working fit throughout said surfaces solely adjacent the point of die operation.

2. The combination of claim 1 in which the mating surfaces of the pin and sleeve comprise frusto-conical surfaces.

3. The combination of claim 1 in which the mating surfaces of the pin and sleeve comprise stepped cylindrical surfaces.

4. The combination of claim 1 wherein the sleeve comprises a bushing fast to said other platen.

5. The combination of claim 1 wherein said leader pin comprises a mounting part and a separable terminal sleeve part, said parts being provided with a coupling uniting said parts during normal leader pin action, said coupling being disengageable to permit the sleeve part to move with the said other platen during the course of separation of the platens, said terminal sleeve and first mentioned sleeve having said complementary surfaces.

6. In a die set having platens movable toward and away from each other, the combination with a leader pin fixed to one of said platens and a bearing bushing fixed to the other said platen, said bushing and pin having complementary stepped cylindrical bearing surfaces concurrently slidably engageable with close fit in the relatively proximate position of the platens in which the die is operative, and laterally free of engagement and in loose guiding fit in relatively separated positions of the platens.

7. The device of claim 6 wherein the cylindrical surfaces on the bushing are axially spaced.

8. The device of claim 6 wherein the bushing comprises a unitary sleeve fitting the punch holder, said sleeve having stepped bearing surfaces embossed inwardly to progressively smaller diameters in the direction of platen separation.

9. The device of claim 6 wherein the bushing comprises a plurality of axially spaced bearing sleeves extending inwardly to progressively smaller diameters in the direction of platen separation and corresponding to the respective pin diameters, and spacers between said sleeves.

10. The device of claim 6 wherein said pin comprises separable sections and frangible connecting means.

11. In a die set comprising relatively movable platens having coating leader pin and bushing means, the combination with a leader pin, of a terminal cap sleeve embracing an end portion of the pin and externally provided with a bearing surface for bushing engagement, and means detachably connecting said sleeve to the pin, whereby the pin may be freed in the event the cap sleeve sticks in the bushing.

12. The device of claim 11 in which the pin and sleeve have mutually engaged bearing surfaces relatively smaller in diameter near the end of the pin than remote from said end, whereby to give immediate increase in radial clearance upon axial relative movement in a direction of sleeve removal upon detachment of said connection.

13. The device of claim 11 in which the detachable connecting means comprises a screw in the end of the pin, said sleeve having abutment and retainer means spanning the end of the pin in fixed connection with the sleeve and engaged by the screw.

14. The device of claim 13 in which the sleeve has a groove in its inner periphery and said retainer means comprises a circular member marginally engaged in the groove and with which the abutment means is fastened to be positioned in the sleeve.

15. The device of claim 13 in which the screw is headed and is frangible for the detachment of said connection to release the pin from the sleeve when tension is excessive.

16. The device of claim 13 in which the screw is headed and the abutment and retainer means comprise a thrust surface overlying the screw head to detach the sleeve and pin positively by effecting relative axial movement in a releasing direction when the screw is unscrewed from the pin.

17. The device of claim 11 in which the pin and sleeve have mutually engaged bearing surfaces relatively smaller in diameter near the end of the pin than remote from said end, whereby to give immediate increase in radial clearance upon axial relative movement in a direction of sleeve removal upon detachment of said connection, the bearing surfaces including axially spaced portions between which there is clearance between the sleeve and pin.

18. The device of claim 11 in which the pin and sleeve have mutually engaged bearing surfaces relatively smaller in diameter near the end of the pin than remote from said end, whereby to give immediate increase in radial clearance upon axial relative movement in a direction of sleeve removal upon detachment of said connection, the said surfaces being frusto-conical.

19. In a die set comprising relatively movable platens having coating leader pin and bushing means, the combination with a leader pin, of a terminal cap sleeve embracing an end portion of the pin and externally provided with a bearing surface for bushing engagement, and means detachably connecting said sleeve to the pin, whereby the pin may be freed in the event the cap sleeve sticks in the bushing, together with a bushing complementary to the sleeve, the sleeve and bushing having mating bearing surfaces of slightly smaller diameter at the outer end of the sleeve than adjacent the pin to provide a close bushing and sleeve fit at both ends of the sleeve during die action and increased radial clearance but effective guidance in relative movement to and from the point of die action.

20. The device of claim 19 in which the sleeve and pin also have complementary and normally engaged bearing surfaces of smaller diameter at the end of the pin than the diameter remote therefrom to provide increased radial clearance between the cap sleeve and pin upon relative pin withdrawal consequent upon detachment of said connection.
